INVENTOR.

UNITED STATES PATENT OFFICE.

ROBERT GAIR, OF NEW YORK, N. Y.

DESIGN FOR A DOILY.

No. 38,968.

Specification for Design.

Patented Dec. 31, 1907.

Application filed July 26, 1907. Serial No. 385,757. Term of patent 3½ years.

To all whom it may concern:

Be it known that I, ROBERT GAIR, a citizen of the United States, residing at New York, borough of Brooklyn, in the county of Kings, State of New York, have invented a new, original, and ornamental Design for Doilies, of which the following is a full, clear, and exact specification.

In the accompanying drawing the figure is

a plan view of a doily, showing my design.

I claim,

The ornamental design for a doily, as shown.

ROBERT GAIR.
